UNITED STATES PATENT OFFICE.

FRANK MESKER AND THOMAS O. ARBEGUST, OF ST. LOUIS, MISSOURI.

WINDOW-FRAME.

SPECIFICATION forming part of Letters Patent No. 448,355, dated March 17, 1891.

Application filed May 3, 1890. Serial No. 350,533. (No model.)

To all whom it may concern:

Be it known that we, FRANK MESKER and THOMAS O. ARBEGUST, of St. Louis, Missouri, have jointly made a new and useful Improvement 5 in Window-Frame Construction, of which the following is a full, clear, and exact description.

The improvement relates more especially to box window-frames having the stiles formed 10 of sheet metal; and it consists more especially in the mode of uniting the outer face of the stile with the adjacent structure and with the sheet-metal column, substantially as is hereinafter set forth and claimed, aided by the 15 annexed drawing, making part of this specification, in which the improved construction is shown in horizontal section taken between the top and bottom of the window-frame.

Only those portions of the construction are 20 shown which are essential to an understanding of the improvement.

A A' represent the sashes of the window, B B' the stiles, C C' the inside finish-boards, D D' the inside sash-stops, E E' the studs of 25 the adjacent wall, F F' the plaster coat, and G G' the sheet-metal columns which respectively adjoin the stiles, H H the sash-weights, and I the stool, all substantially as in previous window-frame constructions, saving as 30 modified by the improvement under consideration, which is as follows:

J represents a strip nailed to the stud E. A similar strip J' is similarly nailed to the stud

E'. The strip is applied to the side e of the stud, and its outer edge j projects outward beyond the line of the outer end e' of the stud. 35 The outer face b of the stile is turned at b' against the outer side, j' of the projecting strip edge j, and is then turned again and laid against the face e² of the stud, and is nailed to thereto substantially as shown. The edge g of the column side g' is then laid against the part b' of the stile-face, and is nailed to said part b' and to the strip J, substantially as shown. 40

We claim—

1. The combination of the sheet-metal stile, the stud, and the strip J, said strip being secured to said stud, as described, and said stile-face being secured to the projecting edge of 50 said strip, substantially as described.

2. The combination of the sheet-metal stile, the stud, the strip secured to and projecting outward beyond said stud and the column, substantially as described. 55

3. The combination of the sheet-metal stile, inside finish-board, stud, and projecting strip J, substantially as described.

Witness our hands this 30th day of April, 1890.

FRANK MESKER.
THOMAS O. ARBEGUST.
